UNITED STATES PATENT OFFICE.

LEO SCHWEIKOWSKI, OF GARRETT, PENNSYLVANIA.

DESIGN FOR A PUZZLE GAME.

60,738.

Specification for Design. Patented Mar. 28, 1922.

Application filed September 10, 1921. Serial No. 499,825. Term of patent 3½ years.

To all whom it may concern:

Be it known that I, LEO SCHWEIKOWSKI, a citizen of the United States, residing at Garrett, in the county of Somerset and State of Pennsylvania, have invented a new, original, and ornamental Design for a Puzzle Game, of which the following is a specification, reference being had to the accompanying drawings, forming part thereof.

The figure is a perspective view of a puzzle game showing my new design.

I claim:

The ornamental design for a puzzle game, as shown. In testimony whereof I have affixed my signature.

LEO SCHWEIKOWSKI.
